FOLDABLE WRENCH SET

Hilton A. Rudd, Sr., Woodbridge, Va.

Application June 1, 1956, Serial No. 588,677

3 Claims. (Cl. 81—71)

This invention relates generally to wrenches, and is more particularly concerned with sets of wrenches in which each individual wrench may be employed as desired yet remaining a part of the set.

A primary object of the invention is to provide a novel improved foldable wrench set in which pairs of wrench members are disposed in oppositely extending relationship from a support hub, the wrench set including a plurality of support hubs pivotally mounted in relatively pivotal relationship on a common pivot shaft wherein when the wrench set is unfolded wrench members are disposed in substantially right angular relation affording handle means for rotating the wrench member to be used, and when the wrench set is folded the wrench members are disposed in substantially longitudinal alignment taking up a minimum amount of space in a tool chest, for example.

A further object of the invention in conformance with that set forth is to provide a novel wrench set of the character involved wherein the wrench members have different polygonal cross sections commonly known as "Allen" wrenches for matching sockets formed in the heads of screws or the like which have a similar polygonal recess in the heads thereof.

A further object of invention in conformance with that set forth is to provide a novel foldable wrench set of the character set forth which is readily and economically manufactured, easily used, and highly satisfactory and practical for the purpose intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top plan view of one embodiment of the novel foldable wrench set, showing the wrench members in their unfolded position;

Figure 2 is an elevational view of the novel wrench set in its unfolded position;

Figure 3 is a top plan view of the novel foldable wrench set in its folded position;

Figure 4 is a fragmentary sectional view taken substantially on line 4—4 of Figure 2;

Figure 5 is a top plan view of another embodiment of the novel foldable wrench set, showing the wrench set in its folded position, and showing by means of phantom lines the disposition of the wrench members when the wrench set is unfolded;

Figure 6 is an exploded perspective view of the wrench set of Figure 5;

Figure 7 is a fragmentary sectional view taken substantially on line 7—7 of Figure 5; and

Figure 8 is an end elevational view looking substantially from line 8—8 of Figure 5, showing the angular relationship of the wrench members on one hub member relative to the longitudinal axis of the pivot shaft upon which the hub members are mounted.

Referring to the drawings in detail, considering Figures

2

1 to 4, the novel wrench set is indicated generally at 10 and includes a pair of support hub members 12 and 14, which may be circular if desired, said hub members having overlying transverse bore portions receiving there-through a pivot shaft 16 affording relative rotation between the support hub members.

The support hub 12 has extending laterally from opposite sides thereof in offset relationship relative to the longitudinal axis of the pivot shaft 16 elongated wrench members 18 and 20, inner end portions 22 and 24, respectively, being received in suitable bore portions extending into the opposite sides of the support hub member. The wrench members 18 and 20 have a polygonal cross section, hexagonal if preferred to define different sizes of "Allen" wrenches.

The support hub member 14 has extending from opposite sides thereof in suitably conformed bore portions ends of elongated wrench members 26 and 28, the longitudinal axis of which being in substantial alignment with the longitudinal axis of the pivot shaft 16. The wrench members 26 and 28 also have a polygonal cross section, each of which being of a different size, and also being of a different size relative to the wrench members 18 and 20.

25 The wrench members 18 and 20 incorporate an intermediate angular bend portion 30 and 32, respectively, wherein the longitudinal axis of the terminal end portions of the wrench members 18 and 20 will be in substantially planar alignment with the longitudinal axis 30 of the wrench members 26 and 28. Thus when the wrench members 18 and 28, and 20 and 26 are disposed in their folded position, the longitudinal axis of the same will be disposed in substantially planar and parallel alignment with respect to each other. Thus when the wrench 35 members are folded into the position shown in Figure 3, the wrench set will take up a minimum amount of space in a tool kit, thus facilitating storage of the same. When the wrench members are unfolded or disposed in the position shown in Figure 1, and it is desired to use, for example, the wrench member 26, the wrench members 18 and 20 will serve as a handle thus affording means for readily manipulating the wrench member 26.

Considering Figures 5 through 8, indicated generally at 40 is the novel wrench set which includes support hub members 42 and 44, similar to those previously described, secured for relative rotation by means of a transverse pivot shaft 46. The support hub 42 has extending from opposite sides thereof elongated wrench members 48 and 50, the inner ends of which being received in a suitably 50 conformed bore portion in the support hub member 42. The support hub member 44 has extending from opposite sides thereof in suitably conformed recess portion the elongated wrench members 52 and 54.

The inner ends of all of the wrench members 48 through 52 extend in substantially aligned relationship relative to the longitudinal axis of the pivot shaft 46, however, the wrench members 48 and 50 include an intermediate angular bend portion 56 and 58, respectively, disposing the terminal end portions of the wrench members 48 and 50, see Figure 8, in angular relationship relative to the longitudinal axis of the pivot shaft 46. Thus when the wrench set is folded in the position shown in Figures 5 and 8, the longitudinal axis of the terminal end portion of the wrench members 48 and 50 will be in substantial planar and longitudinal alignment with the longitudinal axis of the wrench members 52 and 54, respectively. It will be noted that the intermediate angular bend portions 56 and 58 of the wrench members 48 and 50, respectively, extend at opposite or opposed angles 65 with respect to each other relative to the longitudinal axis of the pivot shaft.

Each of the wrench members 48 through 54 have a

polygonal cross section, hexagonal if preferred, and are of a different size thus providing the wrench set.

Thus in the embodiment shown in Figures 5 through 8 as in the embodiment of invention of Figures 1 through 4, there has been provided a novel foldable wrench set which fully conforms with the objects of invention heretofore set forth.

Various positional directional terms such as "inner," "outer," etc. utilized herein have only a relative connotation to aid in describing the device and it is not intended to require any particular orientation with respect to any external elements.

The foregoing is considered to be illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the appended claims.

What is claimed is:

1. A foldable wrench set comprising a pair of overlying hub members, a pivot shaft extending transversely through the hub members permitting relative rotation therebetween, pairs of elongated wrench members extending in overlying relationship from opposite sides of said hub members, each of said wrench members having a different polygonal cross section, the pairs of wrench members being disposable substantially at right angles in use, and foldable into substantial longitudinal alignment when in stored position, one pair of wrench members on one of the hub members including intermediate angular bend portions extending toward the other hub member disposing the longitudinal axes of the terminal end portions of said one pair of wrench members in substantial parallel alignment with the longitudinal axes of the other pair of wrench members when in stored position.

2. A foldable wrench set comprising a pair of overlying hub members, a pivot shaft extending transversely through the hub members permitting relative rotation therebetween, pairs of elongated wrench members extending in overlying relationship from opposite sides of said hub members, each of said wrench members having a different polygonal cross section, the pairs of wrench

members being disposable substantially at right angles in use, and foldable into substantial longitudinal alignment when in stored position, one pair of wrench members on one of the hub members including intermediate angular bend portions extending toward the other hub member disposing the longitudinal axes of the terminal end portions of said one pair of wrench members in substantial parallel alignment with the longitudinal axes of the other pair of wrench members when in stored position, each of said one pair of wrench members extending laterally from said one hub member in offset relationship relative to the longitudinal axis of the pivot shaft, the other pair of wrench members extending laterally from the other hub member in alignment with the longitudinal axis of the pivot shaft.

3. A foldable wrench set comprising a pair of overlying hub members, a pivot shaft extending transversely through the hub members permitting relative rotation therebetween, pairs of elongated wrench members extending in overlying relationship from opposite sides of said hub members, each of said wrench members having a different polygonal cross section, the pairs of wrench members being disposable substantially at right angles in use, and foldable into substantial longitudinal alignment when in stored position, one pair of wrench members on one of the hub members including intermediate angular bend portions extending toward the other hub member disposing the longitudinal axes of the terminal end portions of said one pair of wrench members in substantial parallel alignment with the longitudinal axes of the other pair of wrench members when in stored position, each of said one pair of wrench members extending laterally from said one hub member in opposed angular relationship relative to the longitudinal axis of the pivot shaft, the other pair of wrench members extending laterally from the other hub member in alignment with the longitudinal axis of the pivot shaft.
